UNITED STATES PATENT OFFICE.

ROBERT DINSMORE, OF WESTON, WEST VIRGINIA, ASSIGNOR OF ONE-HALF
TO ADOLF GREENSTEIN, OF SAME PLACE.

PIPE AND SHAFT COUPLING.

SPECIFICATION forming part of Letters Patent No. 462,894, dated November 10, 1891.

Application filed April 22, 1891. Serial No. 389,949. (No model.)

To all whom it may concern:

Be it known that I, ROBERT DINSMORE, a citizen of the United States, residing at Weston, in the county of Lewis and State of West Virginia, have invented a new and useful 5 Pipe and Shaft Coupling, of which the following is a specification.

This invention relates to improvements in pipe and shaft couplings, the objects in view 10 being to provide a simple, cheap, and convenient means of coupling the sections of shafts or pipes in such manner as to form tight joints, readily assembled and disassembled, and this without the necessity of direct handling of the joints during the formation by the 15 operators.

Other objects and advantages of the invention will appear in the following description, and the novel features thereof will be particularly pointed out in the claim.

Referring to the drawings, Figure 1 is a perspective of a joint formed by a pipe-coupling constructed in accordance with my invention. Fig. 2 is a vertical longitudinal section. Figs. 25 3 and 4 are details of the respective members of the joint. Fig. 5 is an enlarged section to show how the heads of the studs fit on the ways provided within the slots of the other section.

Like numerals of reference indicate like 30 parts in all the figures of the drawings.

1 designates a pipe-section, the front end of which is slightly reduced and in rear of its reduced portion provided with a short section 35 2 of screw-threads, upon which is threaded the hub 3 of a coupling-disk 4, which disk has its face located in rear of the end of the section 1, as shown. A leather or other packing-washer 5 encircles the section 1 in front 40 of the disk 4, and is surrounded by a series of square-headed pins 6, projecting from the face of the disk 4.

7 designates the companion pipe-section, and the same is threaded at its inner end, as 45 shown, and receives the rear end of a sleeve 8, which latter at its inner end extends beyond the inner end of the section 7 and terminates in an annular flange 9.

10 designates a coupling-disk, provided 50 with a central opening 11, so as to fit the sleeve 8 and upon its front face with an annular

recess 12, in which is seated the annular flange 9 of the sleeve 8. The disk 10 is provided at intervals with key-hole slots 13, the large portions of which are adapted to receive the heads 55 of the pins or studs 6, and said studs are somewhat shorter than the slots, so that they do not extend completely through the same when entered therein. Each of the key-hole slots is curved concentric with the pipe-sections, and is provided with a pair of upwardly-inclined internal flanges 14, leading from the larger ends of the slots to the narrow ends thereof.

In forming the joint the inner end of the section 1 is inserted into the sleeve 8 until it abuts against the end of the section 7, the intervening space between these sections therefore being covered by the sleeve. The pins or studs entering the key-hole slots may be made 60 to bind the two coupling-disks together by simply partially rotating one of said disks, and thereby forcing the heads of the studs to ride up the inclined ways or flanges of the key-hole slots and thus form a tight joint. 65

In lowering one section upon another, as when in the act of forming well-tubing, it will be obvious that the section 7 may by suitable ropes or chains be lowered upon the section 1, and after the end of the section 1 has been entered in the inner end of the sleeve 8 it will be 70 apparent to the operator that the sections are in alignment, and it is simply necessary in order to effect a coupling and form a joint to rotate the upper section until the disk 10 engages with the pins or studs, and then by 75 partially rotating the disk 10 the coupling is effected. It will be obvious that in such lowering and assembling of the parts the danger of misplacing the washer 5 is avoided, in that the latter is held to its place by reason of the inner end of the sections being extended beyond the washer. This may constitute the entire 80 coupling; but I prefer to employ a locking device; whereby a separation of the coupling becomes impossible. This locking device consists of a wedge-shaped tapered locking-pin 85 15, which, after the coupling is in a locked position, is driven through a convenient key-hole slot 13 and through an oblong slot 16, formed in the disk 4 at one side of one of the studs. A 90 retrograde movement upon the part of either of

95 100

the disks, and hence an unfastening of the two disks, is rendered impossible. However, by withdrawing the pin and employing a wrench or other means, the disks may be rotated so as to bring the heads of the studs to the large ends of the key-hole slots, and thus a separation may be effected.

It will be understood that this invention may be advantageously employed in coupling shafts as well as pipes.

Having described my invention, what I claim is—

The combination, with the opposite pipe or shaft sections, of the disk 4, threaded on the same back of the end thereof and provided with threaded studs arranged in an annular series, at one side of one of which is formed the slot 16, the sleeve 8, having the flange 9 mounted upon the opposite pipe-section and

receiving the adjacent end of the first section, 20 the disk 10, having a central opening 11, loosely mounted upon the sleeve and provided upon its inner face with an annular recess 12 for receiving the flange 9 of the sleeve and also provided with a series of key-hole slots 13, 25 having opposite internal inclined ways or flanges 14 for interlocking with the studs, and the pin 15, passed through one of the slots and through the opening 16 of the disk 4, substantially as specified.

In testimony that I claim the foregoing as my own I have hereto affixed my signature in presence of two witnesses.

ROBERT DINSMORE.
